Attorney

UNITED STATES PATENT OFFICE

EDWARD GROSZ, OF DYSART, IOWA

PENCIL

Application filed February 15, 1929. Serial No. 340,085.

This invention relates to certain new and useful improvements in a pencil, and especially in a pencil of the mechanically operated type, and has for its primary object the provision of a novel connection between the lead carrier and the pushing element for the carrier.

A still further object of the invention is to provide a pencil of the character above described, which is of simplified construction, whereby the separate elements of the pencil may be readily and easily assembled, and otherwise well adapted for the purpose designed.

15 A further object of the invention is to provide a novel cushioning means for the lead holder, which will greatly enhance the writing qualities of the pencil, and at the same time greatly decrease the danger of breaking 20 the lead when undue pressure is exerted upon the pencil while writing.

Further objects and advantages of the invention will present themselves from time to time during a study of the following description taken in connection with the accompanying drawing wherein:

Figure 1 is a longitudinal sectional view through the improved pencil, and

Figure 2 is a longitudinal view partly in section showing the improved connection between the pusher element and the lead holder.

When reference is had to the drawing it will be seen that the pencil comprises an outer casing or shell 5 which is provided at its opposite longitudinal ends with reduced externally threaded portions 6. Screw threadedly connected to one of the reduced portions 6 is a conical pointed member 7 as shown in Figure 1 of the drawings, while with the other end is screw threadedly engaged an apertured cap 8. Suitably mounted within the casing and projecting through the apertured cap 8 is a hollow shaft 9. To that portion of the hollow shaft 9 which projects through the opening 10 formed in the cap 8 is frictionally engaged a cap 11.

Attention is called to the fact that the shaft 9 at one end reaches well into and fits loosely within the conical point 7, while a

shoulder 13 is formed on the upper portion of the shaft adapted to rest against the under surface of the cap 8 adjacent the aperture 10; and upon the topmost edge of the casing 5. The lower end of the shaft 9 is 55 provided with a spiral slot 14, which extends for substantially one-half of the shaft, transforming this portion of the shaft into a worm.

Carried within the worm portion of the shaft is a conical lead carrier 15, the walls of the lead carrier are bent inwardly as at 15', to provide an internal abutment 15^a for the rear end of a lead within the carrier. The upper portion of the lead carrier is provided with a reduced extension as at 16 for a purpose to be hereinafter set forth. Also arranged within the worm portion of the shaft 9 is a lead pusher 19, which consists of a relatively large section 17 having a reduced 65 extension 18 at one end and a thin metallic rod or needle 19 extending from the reduced portion 18. A lateral extending finger 20 projects from the pusher 17 through the spiral slot 14 of the shaft 9. It is yet to be 70 mentioned that a slot 22 is formed on the inner wall of the casing 5 extending longitudinally for the full length of the casing, and it is into this slot that the finger 20 projects and rides up and down in the casing so as 75 to prevent rotation of the pusher when the shaft 9 is being rotated for advancing or retracting the pusher.

When the lead holder 15 and the pusher 80 17 is assembled, it will be seen that the needle 19 extends into the carrier for a predetermined distance, while a spring 23 surrounds the needle 19 and has one end suitably fastened to the reduced portion 16 of the carrier 15 and the other end fastened to 85 the reduced portion 18 of the pusher 17. This spring 23 acts as a cushioning means for the lead when the pencil is in use, in addition to its function as a resilient connection between pusher 17 and the carrier 90 or holder 15.

When in position for use in the carrier the lead is securely retained in the carrier, and means of the abutment 15^a formed within 95 the carrier, against which the rear or inner 100

end of the lead abuts, the said rear or inner end of the lead will be maintained in spaced relation to the inner end of the appendage or pen 19, so as, at all times, to be out of engagement with the said appendage or pen 19. The purpose of so positioning the lead within the holder is that when undue pressure is exerted upon the lead when using the pencil the lead instead of breaking off is permitted to slide inwardly of the casing with the holder 15 axially of the shaft 9, thus permitting a somewhat reciprocatory movement of the carrier or holder independently of the pusher, the normal space between the inner or rear end of the lead and the inner end of the pen or appendage 19 permitting of such movement of the carrier without endangering the breaking of the lead.

20 When it is desired to advance the carrier so as to position the lead beyond the point of the pencil to be used, the cap 11 which has frictional engagement with the tube or shaft 9 is rotated in one direction 25 to rotate the worm which is an integral part of the shaft for operating the pusher whereby both the pusher and carrier are advanced until the lead projects the desired distance beyond the point of the pencil.

20 It will also be appreciated, that when through use, or any other reason, the lead has been so worn as to require the ejection of the lead out of the holder and its substitution by a new piece of lead, the pusher 35 and carrier may be advanced in the manner set forth, until the carrier or holder 15 is projected beyond the lower end of the worm 14. By continually rotating the tubular shaft 9, it is obvious that the needle 40 19 will be forced through the holder 15 so that the lower or inner end of said needle 19 will come into contact with the inner end of the lead within the holder, and by continued rotation of the shaft 9, the said 45 needle will be forced through the holder for ejecting the lead from the holder, the pusher 17 and needle 19 being so actuated against the tension of spring 23.

It is obvious then that when the end of 50 the pencil is in use, the lead in the holder 15 being spaced from the needle 19 permits reciprocating movement of the holder upon the needle and this in conjunction with the spring 23 acts as a cushion for the lead while 55 writing.

To withdraw the lead within the pencil it is merely necessary to rotate the cap 11 in an opposite direction whereby the pusher and carrier are retracted within the worm.

From the foregoing it will be seen that my improved pencil is simple and practical to construct, and greatly enhances the writing qualities of pencils of this type.

65 Having thus described the invention, what

I claim as new and desire to secure by Letters Patent is:—

1. A pencil comprising a casing, a hollow shaft rotatable in the casing, manual operating means for the shaft, a spiral slot formed in the lower portion of the shaft, a lead carrier movable within the shaft, and provided with means for retaining a lead in the carrier against axial movement in one direction, a carrier pusher, a slot formed on the inner wall of the casing and extending longitudinally for the full length of the casing, a lug formed on the pusher for engagement with both slots, said lug adapted for movement within the longitudinal slot to prevent rotation of the pusher upon actuation of said shaft, and a spring interconnecting the pusher and carrier, and adapted to normally hold the pusher in spaced relation to said carrier.

2. A pencil comprising a tubular casing, a lead carrier reciprocable in the casing, said carrier having means to grip a lead and for retaining the lead against axial movement in one direction relative to the carrier, a carrier pusher movable in the casing above said carrier and having a yieldable connection with the carrier whereby said carrier is adapted to reciprocate within the casing independently of the said pusher, without affecting the normal position of a lead within the carrier, and means for actuating said pusher.

3. A pencil comprising a tubular casing, a lead carrier reciprocable in the casing, said carrier having means to grip a lead and for retaining the lead against axial movement in one direction relative to the carrier, a carrier pusher movable in the casing above said carrier, means for moving said carrier pusher, said carrier pusher having a yieldable connection with the carrier, whereby said carrier is adapted to reciprocate within the casing independently of the said pusher, without affecting the normal position of a lead within the carrier, and said pusher having an appendage projecting into said carrier normally retained in spaced relation to the lead within the carrier by said yieldable connection, but adapted to engage the lead for ejecting the same from the carrier upon continued movement of said pusher when said carrier has reached its limit of movement in one direction within said casing.

4. A pencil comprising a casing, a hollow shaft rotatable in the casing, a tubular lead carrier reciprocable in said shaft, said carrier having means to grip the end of a lead, and an abutment for the rear end of the lead, a carrier pusher reciprocable in said shaft above said carrier, said pusher having an appendage projecting into said carrier, a lug extending laterally from the pusher, a spring connection between said pusher and

5 said carrier normally retaining said pusher in spaced relation to the carrier, said casing provided with a longitudinal slot in its inner wall, a spiral slot formed in said shaft to cooperate with said lug and said longitudinal slot for advancing and retracting said carrier.

5. A pencil comprising a casing, a hollow shaft rotatable in the casing, a lead carrier
10 movable in said shaft, a carrier pusher movable in said shaft above the carrier, yielding means operatively connecting the carrier and pusher in spaced relation to one another whereby both are adapted for simultaneous movement within said shaft, and for
15 movement relative to one another when either said carrier or said pusher is in a relatively fixed position, means operatively connecting said shaft and said pusher for
20 effecting said simultaneous movement of the pusher and carrier for moving said pusher relative to the carrier when the latter has reached its limit of movement in one direction, means carried by said carrier to grip
25 one end of a lead for retaining the latter in the carrier against axial movement in one direction relative of the carrier, and said pusher having an appendage projecting into said carrier normally spaced from the
30 said end of a lead and adapted to engage said end of a lead, upon continued movement of said carrier pusher when said carrier has reached the limit of movement in said one direction for ejecting the lead from the
35 carrier.

In testimony whereof I affix my signature.

EDWARD GROSZ.
